UNITED STATES PATENT OFFICE.

WILLIAM ALFRED TAYLOR, OF DETROIT, MICHIGAN.

AUTOMOBILE ALARM.

1,417,217.

Specification of Letters Patent. Patented May 23, 1922.

Application filed July 25, 1921. Serial No. 487,265.

To all whom it may concern:

Be it known that I, WILLIAM A. TAYLOR, a citizen of the United States, residing at Detroit, in the county of Wayne and State 5 of Michigan, have invented a new and useful Automobile Alarm, of which the following is a specification.

This invention relates to a burglar alarm or attachment to be placed on the wheel of 10 an automobile, one of the objects of the invention being to provide a device of this character which, when moving with the wheel will, when properly set, sound an alarm so as to attract attention.

15 Another object is to provide a burglar alarm of this character which can be easily adjusted into or out of active position without removing it from the wheel provided the owner has a key giving him access to 20 the interior of the structure to enable him to make the necessary adjustment.

With the foregoing and other objects in view which will appear as the description proceeds, the invention resides in the combination and arrangement of parts and in 25 the details of construction hereinafter described and claimed, it being understood that, within the scope of what is claimed, changes in the precise embodiment of the 30 invention shown can be made without departing from the spirit of the invention.

In the accompanying drawings the preferred form of the invention has been shown.

In said drawings 35 Figure 1 is an elevation of a portion of a vehicle wheel, showing the lock applied thereto.

Figure 2 is a section on line 2—2, Figure 1.

40 Figure 3 is an elevation of the clappers and their supporting arms.

Figure 4 is a plan view of the lock.

Figure 5 is an enlarged section on line 45 5—5, showing the clappers and their supporting means housed in inactive positions.

Referring to the figures by characters of reference 1 designates a segmental hollow bell structure adapted to lap two or more spokes of a wheel W. Extending laterally 50 from one face of this structure is a hollow segmental section 2 adapted to be inserted laterally between two of the spokes. It is preferred to have the bell structure upon the inner side of the wheel. The outer side 55 of the segment 2 has an opening 3 therein normally closed by a door 4 provided with

a suitable lock whereby the door can be fastened in shut position and it is impossible to open it without the use of a proper key.

60 Mounted on the inner surface of the door 4 is a box or housing 5 having a door 6 and secured within this housing or box is one end of a lazytongs 7 the other end of which has a disk 8 attached thereto. A lug 65 9 extends from the center of this disk and constitutes a bearing for a strip 10 which is ogee curved so as to provide oppositely curved arms. Pivotaly attached to the free end of each of these arms is a link 11 which, 70 in turn, is loosely connected at 12 to a short rod 13 having a ball or enlargement 14 at its free end forming a clapper.

The segmental section 2 is held in place 75 preferably by a screw 15 extending through the rim of the wheel and into an opening 16 in the top of said section. Thus the alarm cannot be removed without first removing the tire. In addition to this fastening means screws may be directed into the 80 rim from within the housing 1 through additional openings 17 suitably located in the sections 2. Thus even though the tire should be removed and the screw 15 disengaged from the alarm, the said alarm would still 85 be held in place by the supplemental screws.

After the alarm has been secured to the wheel it remains a permanent fixture thereon without detracting to an objectionable extent from the appearance of the wheel. To 90 set the alarm the user opens the door 4, thus getting access to the door 6 which is also open. With the door 4 partially opened the lazytongs 7 are extended so as to project from the section 2 into the housing 1 after 95 which door 4 is completely closed and locked and the clappers 14 will be suspended within the housing 1. It will be apparent that when the wheel is rotated the clappers 14 will successively strike the walls of the housing 1 and as these walls are made of a resonant material the noise produced will serve to attract attention to the vehicle. Thus the danger of theft of the vehicle to which the alarm is attached is reduced to 105 the minimum.

When it is not desired to use the alarm the door 4 can be opened, the lazytongs pulled back into the box 5 and the cover 6 moved to shut position.

110 It is to be understood that when the door or cover 6 is shut the arms of the strip 10

will project from the top and bottom of the box 5 as shown in Figure 5.

What is claimed is:—

1. An alarm comprising a resonant housing, a segmental section extending laterally therefrom for insertion between the spokes of a wheel, a door movably connected to said section, a clapper, and means for supporting the clapper either within the housing in active position or within the extension in inactive position.
2. An alarm comprising a resonant housing, a segmental section extending laterally therefrom for insertion between the spokes of a wheel, a door movably connected to said section, a clapper, and an extensible connection between the clapper and the door for supporting the clapper either within the housing in active position or within the extension in inactive position, and means upon the door for fastening the clapper in inactive position.
3. An alarm including a resonant housing, a segmental section thereon insertible

between spokes of a wheel, a door normally closing said section, an extensible support upon the door, a strip mounted to rotate freely on the support, clappers loosely connected to the ends of the strip for striking the housing when the support is extended, and means for holding the support retracted into the extension.

4. An alarm including a resonant housing, an extension thereon having an opening, a door normally closing the opening, an extensible foldable support mounted upon the door, clappers, a connection between the clappers revoluble on the support, and means for holding the support retracted with the clappers in the extension.

In testimony that I claim the foregoing as my own, I have hereto affixed my signature in the presence of two witnesses.

WILLIAM ALFRED TAYLOR.
